UNITED STATES PATENT OFFICE.

HENRY B. SAUERMAN, OF CHICAGO, ILLINOIS.

MATERIAL-MOVING APPARATUS.

1,159,803.

Specification of Letters Patent.

Patented Nov. 9, 1915.

Application filed February 23, 1915. Serial No. 9,885.

To all whom it may concern:

Be it known that I, HENRY B. SAUERMAN, a citizen of the United States, residing at Chicago, in the county of Cook and State of Illinois, have invented a new and useful Improvement in Material-Moving Apparatus, of which the following is a specification.

My invention relates to improvement in material-moving apparatus of the type comprising, generally stated, an inclined cableway supporting a traveling carriage thereon, with a dumping scraper, or bucket, connected with the carriage, and a hauling-line through the medium of which the movements of the carriage and bucket are controlled; and my objects are to provide an improved form of apparatus of this general type, by which the bucket may be operated to dump at the lower end of the inclined cableway.

Referring to the accompanying drawings, Figure 1 is a view in elevation of an apparatus constructed in accordance with my invention, the apparatus being shown in the position it assumes after the bucket has been loaded and is traveling downwardly on the cableway to the point of dumping; Fig. 2 is a top plan view of the apparatus illustrated in Fig. 1 with the bucket omitted, this view being taken at the line 2 on Fig. 1 and viewed in the direction of the arrow; Fig. 3 is a view similar to Fig. 1, showing the bucket in dumped position; Fig. 4 is a view like Fig. 1 of a modification of the construction therein illustrated; and Fig. 5, a view like Fig. 1 of still another modification.

The inclined cableway which would be supported, in practice, to extend across the material to be moved, as, for example, the ground to be excavated or dredged, is represented at 6, and, in accordance with common practice, is so associated with other parts, not shown, as to permit it to be slackened for permitting the bucket to engage with the material to be moved, and drawn to taut condition preparatory to the operation of transferring the bucket to the point of dumping.

Mounted on the cable 6 to travel thereon is a carriage 7 which, in the construction illustrated, is formed of a pair of frames 8 secured together in spaced relation by spacers 9 and pins 10, the pins 10 having journaled thereon pulleys 11 at which the

carriage is supported on the cableway 6 to adapt it to be moved along the latter.

The dumping scraper or bucket, represented at 12, is of a form generally used, its forward open digging end being provided with a cutting-edge portion 13. According to the arrangement illustrated in Fig. 1, the bucket 12 is supported from the carriage 7 in such a manner that when loaded the center of gravity of the bucket will be toward the rear of the latter, the bucket in this construction being supported from the carriage, by means of a cable 14 which is connected at its opposite ends with an eye 15 on the rear end of the bucket 12, and with a bail 16 on the forward end of the bucket, the cable 14 intermediate its ends running over a pulley 17 journaled on the carriage 7 between the frame-members 8.

The hauling-line, through the medium of which the carriage and bucket are moved along the cableway, is represented at 18 and terminates in sections 19 and 20, the section 20 being connected, as indicated at 20^a, with the forward end of the bucket 12, and the section 19 passing over a pulley 21^a, journaled on a pin 21 on the frame 7 and connecting at one end with the bail 16, as represented. The bucket 12 is also connected at 22^a with one end of a cable 22 which passes over a pulley 23 journaled on the carriage 7, and thence around a pulley 24 journaled on an arm 25 pivotally connected at 26 to the carriage 7 and extending rearwardly therefrom, the end of the cable 22 adjacent to the pulley 24 being provided with a block 27 which straddles the cable 6 and is movable along the latter, the block 27 being provided with a pulley 28 which engages the cable 6 to reduce friction. The block 27 is adapted to coöperate, in a manner herein-after described, with a stop-device 29 adapted to be clamped to the cable 6 at any desired point along the latter, and positioned on the cable below the block 27.

In the operation of the apparatus described, the line 6 is first slackened to allow the bucket 12 to engage with the material to be moved, whereupon the hauling-line 18 is drawn on, causing the bucket to fill. The operator then causes the cable 6 to become more or less taut as conditions render it desirable, thus lifting the bucket 12 away from the material on the ground and permitting it and the carriage to move down the cableway 6 under the control of the operator paying,

out the hauling-line 18. When the carriage moves down on the cable 6 to a position in which the block 27 engages the stop 29, the block 27 is arrested in its downward movement along the cableway 6, and continued movement of the carriage downwardly along the cableway will thus cause the bucket to be moved to the dumping position represented in Fig. 3, the cable 14 in this operation running over the pulley 17. As the center of gravity of the loaded bucket is toward the rear end thereof, the movement for rolling the bucket into dumping position is against gravity and is strictly under the control of the operator handling the hauling-line 18, and thus the roll-over movement may be a gradual or a rapid one, as desired.

It will be understood that by adjusting the stop 29 along the cableway 6, the dumping of the bucket may be effected at any desired point on the cable. It will be readily understood from the foregoing description and the drawings that, following the dumping of the bucket (Fig. 3), the same may be readily righted by pulling on the hauling-line 18.

The apparatus illustrated in Fig. 4 is the same as that illustrated in Figs. 1, 2 and 3, excepting that instead of providing the cable 14 connected at its opposite ends with the bucket and passing over the pulley on the carriage 7, and attaching one end of the cable 19 to the bail 16, this end of the cable 19 is attached directly to the carriage, as represented at 30, and a cable 31, connected with the bail 16 of the bucket and fixed to the carriage, as indicated at 32, is provided. It will be readily understood from the foregoing that the operation of the apparatus just described is substantially the same as that of the apparatus shown in Fig. 1, the bucket 12 being in effect pivoted on the cable 31.

The apparatus illustrated in Fig. 5 is the same as that illustrated in Fig. 1, excepting in the particular of the connection of the cable 22 with the bucket. In this construction, instead of attaching one end of the cable 22 to the bucket, this end of the cable 50 extends over a pulley 33 journaled on the rear end of the bucket, and attaches to the carriage 7 at the point indicated at 34. It will be readily understood that with the pulley arrangement thus provided, the travel of the bucket 12, when the cable 22 is drawn on by engagement of the block 27 with the stop 29, will be reduced one-half, as compared with the travel of the bucket in the construction illustrated in Fig. 1, and consequently only about one-half of the power is required to move the bucket to dumping position as is required compared with that in the case of the construction illustrated in Fig. 1. This arrangement of the pulley and cable device, 65 however, necessitates the provision of a

longer bar-member 25 than is provided in the case of the construction shown in Fig. 1.

It will be readily understood from the foregoing that in each of the constructions illustrated, the bucket, when loaded, normally hangs in load-carrying position and it is necessary in turning the bucket to dumping position to act against gravity, which is a great advantage, as the operator may thereby maintain effective control over the 75 bucket in the dumping operation.

While I have illustrated and described certain forms in which my invention may be embodied, I do not wish to be understood as intending to limit it thereto, as the same may 80 be variously modified and altered, and the invention embodied in other forms, without departing from the spirit of my invention. Furthermore, I do not wish to be understood as intending to limit my invention to an 85 apparatus wherein a slack line is employed with a bucket of the type shown operating thereon, as it may be embodied in an apparatus employing a cable co-operating with a bucket in the form of a so-called skip which 90 would be loaded at one elevation, as by dumping the material into it, and then allowed to descend on the line to the point of dumping at which it would be automatically dumped, as explained of the constructions 95 shown.

What I claim as new and desire to secure by Letters Patent is—

1. In apparatus of the character set forth, the combination of an inclined track-cable, 100 a carriage movable thereon and provided with a rearward extension held against longitudinal movement relative to the carriage, a bucket flexibly supported on said carriage with its center of gravity, when loaded, in the rear of its point of support, a hauling-line for the bucket, and means engaging the rear end of said extension operating upon the descent of the carriage on the cable to turn said bucket to dumping position in opposition to gravity.

2. In apparatus of the character set forth, the combination of an inclined track-cable, 115 a carriage movable thereon and provided with a rearward extension disconnected from said cable, a bucket flexibly supported on said carriage with its center of gravity, when loaded, in the rear of its point of support, a hauling-line for the bucket, and means engaging the rear end of said extension operating upon the descent of the carriage on the cable to turn said bucket to dumping position in opposition to gravity.

3. In apparatus of the character set forth, the combination of an inclined track-cable, 125 a carriage movable thereon and provided with a rearward extension disconnected from said cable, a bucket flexibly supported on said carriage with its center of gravity, when loaded, in the rear of its point of sup- 130

port, a hauling-line for the bucket, a stop on said cable, a block running on said cable and adapted to engage said stop on the descent of the bucket, and a cable or chain connected with said block and said bucket in the rear of the center of gravity of the latter and engaging the rear end of said extension and operating when said block engages said stop to turn said bucket to dumping position in opposition to gravity.

4. In apparatus of the character set forth, the combination of an inclined track-cable, a carriage movable thereon and provided with a rearward extension held against longitudinal movement relative to the carriage, a bucket flexibly supported on said carriage with its center of gravity, when loaded, in the rear of its point of support, a hauling-line for the bucket, a stop on said cable, a block running on said cable and adapted to engage said stop on the descent of the bucket, and a cable or chain connected with said block and said bucket in the rear of the center of gravity of the latter and engaging the rear end of said extension and operating when said block engages said stop to turn said bucket to dumping position in opposition to gravity.

5. In apparatus of the character set forth, the combination of an inclined cable, a carriage movable thereon and provided with a rearward extension, a bucket supported on said carriage, with the center of gravity of the bucket, when loaded, in the rear of its point of support, a hauling-line for the bucket, a block running on said cable, a cable or chain connected with said block and with said bucket in the rear of its center of gravity and extending over the pulleys on said carriage, and a stop on said inclined cable adapted to be engaged by said block upon the descent of the bucket on said inclined cable.

the bucket, when loaded, in the rear of its point of support, a hauling-line for the bucket, a block running on said cable, a cable or chain connected with said block and with said bucket in the rear of its center of gravity and engaging said carriage at the rear end of said rearward extension and in advance of the rear end of said rearward extension, and a stop on said inclined cable adapted to be engaged by said block upon the descent of the bucket on said inclined cable.

6. In apparatus of the character set forth, the combination of an inclined cable, a carriage movable thereon and provided with a rearwardly-projecting extension pivoted to the body of the carriage, pulleys on said extension and the body portion of said carriage, a bucket supported on said carriage, with the center of gravity of the bucket, when loaded, in the rear of its point of support, a hauling-line for the bucket, a block running on said cable, a cable or chain connected with said block and with said bucket in the rear of its center of gravity and extending over the pulleys on said carriage, and a stop on said inclined cable adapted to be engaged by said block upon the descent of the bucket on said inclined cable.
